BALLISTOSCOPE

Estle Ray Mann, Upper Montclair, and Samuel Ward Stanton, Glen Ridge, N. J., assignors to Allen B. Du Mont Laboratories, Inc., Passaic, N. J., a corporation of Delaware

Application May 13, 1944, Serial No. 535,494

3 Claims. (Cl. 315—26)

1
This invention relates to an electronic device in which a cathode-ray tube is used in such a way that it operates in a manner similar to a ballistic galvanometer. With this invention an electrical impulse is caused to initiate oscillations of a damped oscillator. These oscillations are caused to control the sweep of the electron beam of an oscilloscope tube.

The electrical impulses may be derived from various sources such as inductances and charged condensers, for example. The sweep of the cathode-ray beam is preferably such that it traces a decreasing spiral on the face of the tube, the initial size of the spiral being utilized to ascertain the desired information or comparative quantities. Since the magnitude of the initial convolution of the spiral is a function of the impulse that is applied to the input terminal of the device, the spiral is used as a visible indication of the desired information.

In carrying out the invention an electrical pulse or charge is taken from a source and its effect on a damped oscillator is observed by means of an oscilloscope to examine the same. For example, the pulse may be taken from a charged condenser to compare its capacity with that of another condenser charged from the same source. The functioning of this device is somewhat like that of a ballistic galvanometer, the electrical properties thereof being analogous to the mechanical properties of a galvanometer.

The device comprises a damped negative resistance oscillator similar to a multivibrator that is provided with a resistance-capacitance tuned tank circuit and means for varying the decrement of the oscillations. Two twin T resistance-capacitance circuits are provided between the control grids of the oscillator, and the electrical characteristics of the twin T network are such that the impedance between the two grids is a maximum at the resonant frequency of the network.

The invention may be understood from the description in connection with the accompany drawing which is a diagram of connections illustrating the invention.

Reference character 1 indicates a terminal to which a signal or impulse, such as a discharge from a charged condenser, for example, is to be applied. This impulse is coupled by condenser 2 to the grid of tube 3 which is indicated as a tetrode, although other types of vacuum tubes may be used. A second tube 4, which is the same sort of tube as tube 3, is used.

A source of positive voltage indicated by the plus sign 5 is connected through load resistors 6 and 7 to the plates of tubes 3 and 4, respec-

tively. A resistor 8 is located between the source 5 and the screen grids of the tubes 3 and 4. Resistors 10 and 11 are connected from the cathodes of tubes 3 and 4 to ground through a variable resistor 16 or 17, which are for fine control of the damping of oscillations. Condensers 12 and 13 are also connected respectively between the cathodes of these tubes and ground. The amount of resistance between cathodes and ground is controlled by having the lead 14 between these resistors connected by switch 15 to either one of the variable resistors 16 or 17.

A switch 18 is provided for connecting the plate of tube 3 by condenser 19 and lead 20 to one end of the resistor 21, which is grounded at the other end. A movable contact 22 on resistor 21 is adapted to be connected by switch 23 to the control grid of the tube 4. A switch 25 is adapted to connect the plate of the tube 4 by condenser 26 and lead 27 to one end of the resistor 28, the other end of this resistor being grounded. A movable contact on resistor 28 is connected to lead 29. This lead 29 may be connected by switch 30 to the control grid of tube 3.

The switches 15, 18, 23, 25 and 30 are ganged to move together. The connections just described are for controlling the feedback from the plates of tubes 3 and 4 to the grids of each other. The switch 18 in the left hand position connects the plate of tube 3 by condenser 32 and lead 33 to one end of the resistor 34, the other end thereof being grounded. The movable contact 35 on resistor 34 is connected by switch 23, in the left hand position, to the grid of tube 4.

The switch 25 in its left hand position connects the plate of tube 4 by condenser 38 and lead 39 to one end of the resistor 40, the other end of this resistor being grounded. The movable contact 41 on resistor 40 can be connected by switch 30 to the grid of tube 3.

A resistance-capacitance circuit consisting of resistors 48, 49, 50 and condensers 51, 52 and 53, provide high Q circuits that are connected by leads 54 and 55 to the feedback leads 20 and 27, respectively, when the switches 18, 23, 25 and 30 are in their right hand positions. Another resistance-capacitance circuit consisting of resistors 58, 59, 60 and condensers 61, 62 and 63 provide high Q circuits that are connected by leads 64 and 65 to the resistors 34 and 40 that are connected to the feedback leads 33 and 39 when the switches 18, 23, 25 and 30 are in their left hand positions.

Condensers 65 and 66 couple the outputs from the tubes 3 and 4 to gain control resistor 67 and 68, respectively. Sliding contactors 69 and 70,

which may be ganged when desired, connect these resistors 67 and 68 to duplicate phase shifting devices, only one of which needs to be described. The adjustable contact 69 on resistor 67 is connected by lead 71 to the control grid of tube 72. The cathode of this tube is biased by resistor 74.

The resistance of resistor 80 which is the load resistor of tube 72 is the same as that of resistor 74. The plate of this tube may be coupled by switch 82 to a low frequency phase shifter consisting of condenser 83 and resistor 84, or to a high frequency phase shifter consisting of condenser 85 and resistor 86. Both of these resistors are connected to ground through the cathode resistor 74. Either one of these phase shifters may be coupled by switch 89 and slideable contacts 87 and 88 to any point on resistors 84 and 86.

The switch 89 is coupled by lead 90 and condenser 91 to a balanced phase inverter deflection amplifier 92 of a known sort represented diagrammatically, by which voltages are generated that are suitable for being applied by leads 93 and 94 to the deflection plates 96 and 97 of the cathode-ray tube 98 which is indicated diagrammatically.

The elements of the other phase shifter, which is connected to the tube 73, are designated by the same reference characters with primes that have been used in describing the phase shifter above. The balanced phase inverter deflection amplifier 103 to which the lead 90' is coupled by condenser 91' provides deflection voltages for the horizontal deflection plates of the oscilloscope tube 98. The leads 104 and 105 from the horizontal deflection amplifier 103 are connected to the horizontal deflection plates 106, 107 as indicated.

The oscilloscope tube 98 may be any one of several known sorts. The heater of this tube is indicated at 110, the cathode at 111, the first and second anodes at 112 and 113; these all being connected to suitable sources of potential in the usual way.

The operation is as follows:

An impulse, for example, such as the discharge from a condenser that may have been charged under conditions to be investigated, is applied to the terminal 1, whereupon damped oscillations are set up in the circuits of tubes 3 and 4. The frequency of these oscillations depend upon which network 48-53 or 58-63 is connected to the grids of tubes 3 and 4. The damping rate of the oscillations depend upon the adjustments of the variable resistors in the oscillator circuits and the positions of the switches 15, 18, 23, 25 and 30 and the positions of the contactors 22, 29, 35 and 41 on resistors 21, 28, 34 and 40, respectively. Both the frequency and the damping can be varied over a wide range.

The trace of the cathode-ray beam on the face of the tube 98 can be made a spiral which spirals toward the center at a rate determined by the damping rate of the oscillations of tubes 3 and 4. The size of the spiral is controlled by the gain control contactors 69 and 70 on resistors 67 and 68. The position of the switches 82 and 82' and the positions of the contactors 87, 87' on resistors 84, 84' and contactors 88, 88' on resistors 86, 86' determine the amount of phase shift of the signals applied to the vertical deflection plates 96, 97 and the horizontal deflection plates 106, 107, so that adjustments can be made to obtain spirals of the desired shape as well as the desired duration.

The sizes of the resistors and condensers indicated on the drawing are illustrative.

What is claimed is:

1. In combination, a pair of vacuum tubes not normally oscillating each comprising a cathode, a control grid, a screen grid and an anode, resistance-capacitance networks comprising resistances and capacitances connected respectively to the control grids of said tubes in a series parallel combination to ground, adjustable means for feeding back energy from the plate circuits of each of said tubes to the control grid circuits of the other tube in amounts sufficient to sustain damped oscillations in said networks, means comprising adjustable resistors between the cathodes of said tubes and ground to control damping of said oscillations, means for applying a pulse of voltage to one of the said control grids to initiate said damped oscillations, a stage of push-pull amplification to amplify said damped oscillations, means for controlling the amounts of voltage applied to the grids of said push-pull amplifiers, and means for shifting the phases of the output signals from said push-pull amplifiers with respect to each other.

2. In combination, a pair of vacuum tubes not normally oscillating each comprising a cathode, a control grid, a screen grid and an anode, resistance-capacitance networks comprising resistances and capacitances connected respectively to the control grids of said tubes in a series parallel combination to ground, adjustable means for feeding back energy from the plate circuits of each of said tubes to the control grid circuits of the other tube in amounts sufficient to sustain damped oscillations in said networks, means comprising adjustable resistors between the cathodes of said tubes and ground to control damping of said oscillations, means for applying a pulse of voltage to one of the said control grids to initiate said damped oscillations, a stage of push-pull amplification to amplify said damped oscillations, means for controlling the amounts of voltage applied to the grids of said push-pull amplifiers, means for shifting the phases of the output signals from said push-pull amplifiers with respect to each other and means to amplify said phase shifted signals.

3. In combination, a pair of vacuum tubes not normally oscillating each comprising a cathode, a control grid, a screen grid and an anode, resistance-capacitance networks comprising resistances and capacitances connected respectively to the control grids of said tubes in a series parallel combination to ground, adjustable means for feeding back energy from the plate circuits of each of said tubes to the control grid circuits of the other tube in amounts sufficient to sustain damped oscillations in said networks, means comprising adjustable resistors between the cathodes of said tubes and ground to control damping of said oscillations, means for applying a pulse of voltage to one of the said control grids to initiate said damped oscillations, a stage of push-pull amplification to amplify said damped oscillations, means for controlling the amounts of voltage applied to the grids of said push-pull amplifiers, means for shifting the phases of the output signals from said push-pull amplifiers with respect to each other, and means to amplify said phase shifted output signals and apply them to an indicating device.
